US00D950921S

(12) United States Design Patent (10) Patent No.: US D950,921 S
(45) Date of Patent: * May 10, 2022

(54) FOOTWEAR

(71) Applicant: Target Brands, Inc., Minneapolis, MN (US)

(72) Inventor: Austyn Dunham, Minneapolis, MN (US)

(73) Assignee: Target Brands, Inc., Minneapolis, MN (US)

() Term: 15 Years

(21) Appl. No.: 29/754,475

(22) Filed: Oct. 12, 2020

(51) LOC (13) Cl. 02-04

(52) U.S. Cl.

USPC D2/970; D2/896

(57) CLAIM

The ornamental design for a footwear, as shown and described.

DESCRIPTION

FIG. 1 is a front, top and right side perspective view of a footwear according to the new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof; and,

FIG. 7 is a back, bottom and left side perspective view thereof.

The bold broken lines represent stitching and are a part of the claimed design. The non-bold broken lines in the drawings show portions that form no part of the claimed design.

1 Claim, 7 Drawing Sheets
